CLAIM

The ornamental design for a metal cryptographic currency card, as shown and described.

DESCRIPTION

FIG. 1 is a top plan view of the first embodiment of the cryptographic currency card showing my new design;

FIG. 2 is a side view, the opposite side being a mirror image thereof;

FIG. 3 is a front view, the rear view being a mirror image thereof;

FIG. 4 is a top plan view of the second embodiment thereof;

FIG. 5 is a side view, the opposite side being a mirror image thereof;

FIG. 6 is a front view, the rear view being a mirror image thereof;

FIG. 7 is a top plan view of the third embodiment thereof;

FIG. 8 is a side view, the opposite side being a mirror image thereof;

FIG. 9 is a front view, the rear view being a mirror image thereof;

FIG. 10 is a top plan view of the fourth embodiment thereof;

FIG. 11 is a side view, the opposite side being a mirror image thereof;

FIG. 12 is a front view, the rear view being a mirror image thereof;

FIG. 13 is a top plan view of the fifth embodiment thereof;

FIG. 14 is a side view, the opposite side being a mirror image thereof;

FIG. 15 is a front view, the rear view being a mirror image thereof;

FIG. 16 is a top plan view of the sixth embodiment thereof;

FIG. 17 is a side view, the opposite side being a mirror image thereof;

FIG. 18 is a front view, the rear view being a mirror image thereof; and,

FIG. 19 is a bottom plan view of each of the above

embodiments shown in FIGS. 1-18.

The broken lines included in FIGS. 1, 10, 13 and 16 represent generic alphanumeric digits with no claim to

specific data, font, or type face and forms no part of the

claimed design.
